United States Patent Office

Des. 223,356
Patented Apr. 11, 1972

223,356

CONTAINER FOR CHLORINE PELLETS OR THE LIKE

Clellmont L. Sharp, 6204 Eagle Lake Drive,
Minneapolis, Minn. 55428

Filed Nov. 2, 1970, Ser. No. 25,766

Term of patent 14 years

Int. Cl. D23—01

U.S. Cl. D23—2

Fig. 1

Fig. 2

FIG. 1 is a top plan view of a container for chlorine pellets or the like showing my new design; and

FIG. 2 is a perspective view thereof.

I claim:

The ornamental design for a container for chlorine pellets or the like, substantially as shown.
